UNITED STATES PATENT OFFICE

2,152,420

LOCOMOTIVE

Frank P. Roesch, Chicago, Ill.

Application October 4, 1937, Serial No. 167,154

15 Claims. (Cl. 105—44)

My invention is designed primarily for use with a modern type of locomotive in which both cylinders and valve chambers, as well as the saddle, are preferably cast in one piece.

5 In carrying out my invention I cast the saddle with a large hollow preferably occupying all the space in the center between the valve chambers, and I conduct the exhaust steam directly therefrom into said space, thereby further expanding 10 the exhaust steam before final emission from the exhaust nozzle, thus effecting a corresponding reduction in the back pressure.

In my invention hereinafter disclosed, I place 15 in a passage between said hollow space and smoke-box a movable valve actuated by exhaust steam pressure against a helical spring in such a manner as will result in a constant predetermined and adjustable back pressure under all 20 conditions of service, thereby creating a fairly constant draft of definite intensity instead of the variable, intermittent and high and low intensity drafts obtaining at present.

A further purpose of my invention is to provide 25 simple means operating automatically to prevent the drawing of the smoke-box gases back into the cylinders while the locomotive is drifting, thus eliminating the present troubles caused by the carbonization of oil in the cylinders, valve 30 chambers, exhaust and steam passages, and the deposit of carbonized matter therein. By doing 35 this, the use of drifting valves and the so-called drifting throttle can be dispensed with, thus reducing the fuel consumption in ratio to the amount of steam now used while drifting.

A further purpose of my invention is to provide 40 means to maintain a fairly uniform flow and quantity of exhaust steam for use in connection with feed water heaters of any type, exhaust steam injectors, etc.

A further purpose is to provide a common 45 chamber into which all exhaust steam from locomotive auxiliaries, such as, boosters, stokers, air compressors, etc., can be diverted, thereby reducing the back pressure frequently encountered in the operation of such devices, and through such reduction in back pressure reduce the amount of steam required in their operation.

To illustrate my invention I annex hereto three 50 sheets of drawings in which the same reference characters are used to designate identical parts in all figures, of which—

Figure 1 is a vertical section through the smokebox, valve chambers, cylinders and saddle as 55 seen on the line 1—1 of Figure 2;

Figure 2 is a horizontal section as seen on the line 2—2 of Figure 1;

Figure 3 is a vertical section as seen on the line 3—3 of Figure 1;

Figure 4 is a vertical section as seen on the line 5 4—4 of Figure 1; and

Figure 5 is a vertical section as seen on the line 5—5 of Figure 2.

The smoke-box 10 may be of any desired construction and as usual is seated on and supported 10 by the saddle 11, which preferably has the cylinders 12 and the associated valve chambers 13 cast integrally therewith with each end of each of the valve chambers having a short passage 14 therefrom leading directly into the capacious 15 hollow 15 of the saddle 11, which hollow is closed except as hereinafter noted. This hollow will have a capacity of from two to four times that of each of the cylinders 12, as indicated by their respective cross sectional dimensions. The customary live steam pipes 16 from the boiler open 20 into the tops and centers of the valve chambers 13 at 17, and each valve chamber has the customary sleeves 18 secured therein towards the ends thereof, which sleeves are provided with the 25 apertures 19 (see Fig. 5) therein which apertures 19 register with the generally annular passages 20 formed in the valve chamber and which are connected by the passages 21 with the ends of the cylinders 12. The customary piston valves 30 22 in the valve chambers, as well as the pistons 23 in the cylinders, are connected to the customary valve rods 24 and piston rods 25, and the entire mechanism operates during the running 35 of the locomotive in the customary manner, the valves 22 controlling the admission of the live steam to one side of the pistons while it exhausts from the other side in the customary manner. The exhaust steam, it will be noted, passes directly from the ends of the valve chambers into 40 the hollow 15 through the passages 14 while the engine is running. When it is drifting, in which case the main throttle valve (not shown) is closed, no steam is admitted to the cylinders 12, the pistons 23 simply pumping the air they contain 45 back and forth in the hollow 15. Customary valves 36, in the bottom of the casting, provide means for automatically draining any condensed steam from the hollow.

When the locomotive is running the exhaust 50 steam is forced through the passages 14 into the hollow 15 raising the pressure therein until it opens the exhaust valve 26 into the smoke-box 10. While this valve may be variously constructed, I preferably employ the specific mecha- 55

nism illustrated, in which a cylindrical chamber 27 is formed as a part of the saddle 11 in which it is located, and has a passage 28 opening upwardly therefrom into the smoke-box 10, which passage 28 will be connected to any desired form of nozzle (not shown) that may be employed to direct the exhaust steam into the smoke stack (not shown). The chamber 27 has its inner end closed by a bushing 29, removable for replacement, which has the orifice 30 therein to admit the exhaust steam which pushes the sliding valve member 31 against the pressure of the helically coiled expanding spring 32 in the other end of the chamber 27, the tension of which is adjusted by the set screw 33 threaded through the disk 34 closing that end of the chamber, and having the disk 35 engaging the spring 32. It will be obvious that the smaller the orifice 30, the greater the resulting cushioning effect that will be produced to prevent slamming of the valve as it will be closed if the pressure of the exhaust steam in the hollow 15 is suddenly reduced. When the engine is at rest, or drifting, and there is no exhaust steam pressure on the valve member 31, the unreduced end thereof closes the passage 28, as well as the openings 36 (see Figure 1) in the chamber 27, so that no smoke can get from the smoke-box 10 into the hollow 15, and thence back to the cylinders 12 and valve chambers 13, where its presence would be highly objectionable.

When the throttle is closed and the engine is drifting, as soon as the pressure in the hollow 15 falls below that for which the valve is set, it is closed by the spring 32, leaving the cylinders 12 and the hollow filled with low pressure exhaust steam containing the customary lubricant in suspension, which serves to keep the cylinders oiled as the exhaust steam is pumped back and forth therein as the engine is drifting, obviating the necessity of furnishing the cylinders with live steam, not needed for propulsion, to keep them lubricated, thus enabling me to do away with the customary drifting valve. When the engine is running and the exhaust steam in the hollow 15 reaches the pressure for which the spring 32 is adjusted, the valve member 31 is moved to the dotted line position and an outlet for the exhaust steam is opened through the openings 36, the reduced portion 37 of the valve member 31, and the passage 28 to the smoke-box 10, where the exhaust steam is discharged in the customary manner through the nozzle (not shown) into the smoke stack (not shown) thus getting the desired forced draft customarily employed.

As the exhaust steam has expanded in the hollow 15 and flows through the opened passage 28 at a comparatively low, but steady pressure, it does away with the annoying short puffs that occur with the ordinary engine when it is working at high pressure, and when there is no opportunity for any expansion of the exhaust steam until it reaches the smoke box, where its sudden expansion produces the aforesaid puff, the loudness of which depends in that case upon the pressure of the exhaust steam. By my invention the forced draft is materially reduced, even when the engine is working under its heaviest load, and as a heavy forced draft is wasteful of fuel, there is also a pronounced saving of fuel by the use of my invention when the engine normally works under a heavy load.

While I have shown and described my invention as embodied in the form which at present I consider best adapted to carry out its purposes, it will be understood that it is capable of modi-

fications, and I do not desire to be limited in the interpretation of the following claims, except as may be necessitated by the state of the prior art.

What I claim as new and desire to secure by Letters Patent of the United States is:

1. In a locomotive engine, the combination with a fire box and boiler having a smoke-box, of a saddle upon which the smoke-box is supported having a large hollow therein, valve chambers and associated cylinders supported from the saddle, short passages from the ends of the valve chambers to the hollow in the saddle into which the steam from the cylinders is exhausted and expanded, an exhaust steam passage from the hollow of the saddle to the smoke-box, a valve in said exhaust steam passage, and means for holding said valve closed until the exhaust steam from the cylinders raises the pressure in the hollow of the saddle to a desired degree.

2. A locomotive engine as described in claim 1, in which there are means for adjusting the pressure required to open said valve.

3. A locomotive engine as described in claim 1, in which the means for holding said valve closed is a spring acting against the same.

4. A locomotive engine as described in claim 1 in which the means for holding the valve closed consists of a spring acting against it, together with means for adjusting the tension of said spring.

5. In a locomotive engine, the combination with a smoke-box, of a saddle upon which the smoke-box is supported having a large hollow therein into which exhaust steam from the cylinders is discharged and expanded, a valve chamber in said hollow supported by the saddle, a passage leading from said valve chamber to the smoke-box, a valve in said chamber movable by the pressure of the exhaust steam in said hollow from a position closing said passage to an open position, an orifice in said valve chamber so that the steam from the hollow can press on the valve, and means for holding said valve closed against said pressure until said pressure reaches a predetermined amount.

6. A locomotive engine as described in claim 5, in which the means for holding said valve closed consists of a spring acting against said valve.

7. A locomotive engine as described in claim 5, in which the means for holding said valve closed consists of a spring provided with means for regulating its tension.

8. A locomotive engine as described in claim 5, in which the orifice in said chamber admitting exhaust steam thereto is reduced to eliminate shock due to slamming as the valve closes.

9. A locomotive engine as described in claim 5, in which the orifice in said chamber admitting exhaust steam thereto is reduced to eliminate shock due to slamming as the valve closes, and in which said orifice is located in a removable bushing.

10. In a locomotive engine, the combination with a fire-box and a boiler having a smoke-box connected therewith, of driving cylinders and valve chambers associated therewith, supporting connections between said smoke-box and the driving cylinders and valve chambers, a large hollow space in said supporting connections between said driving cylinders and valve chambers of greater capacity than that of the combined cylinders and exhaust channels in which the exhaust steam from the cylinders is expanded, direct passages from the ends of the valve chambers to said hollow space, a passage from said

hollow space to said smoke-box, a valve in said hollow space closing said passage but capable of being opened by exhaust steam pressure in the hollow space, and means for holding said valve closed in the absence of a certain degree of exhaust steam pressure in said hollow space.

5 11. A locomotive engine as described in claim 10, in which there are means for regulating the pressure at which said valve opens.

10 12. In an engine, the combination with a fire box and boiler having a smoke box, of a hollow casting supporting the smoke box and having the bodies of the valve chambers and associated cylinders forming a part thereof, the hollow central portion of the casting having a cubical content capacity greater than that of the cylinders and exhaust channels combined, passages from the ends of the valve chambers through which the exhaust steam passes directly to the hollow where

it is expanded, an exhaust steam passage from the hollow central portion to the smoke box, a valve controlling said passage and means for holding said valve closed until the exhaust steam from the cylinders raises the pressure in the hollow of the casting to a desired degree.

13. A locomotive engine as described in claim 12 in which there are means for adjusting the pressure required to open said valve.

14. A locomotive engine as described in claim 12 in which the means for holding the said valve closed is a spring acting against the same.

15. A locomotive engine as described in claim 12 in which the means for holding the valve closed consists of a spring acting against it, together with means for adjusting the tension of said spring.
